UNITED STATES PATENT OFFICE.

ERNST JOSEPH SCHMIDT, OF HAMBURG, GERMANY.

BOILER-FURNACE.

SPECIFICATION forming part of Letters Patent No. 669,666, dated March 12, 1901.

Application filed January 8, 1901. Serial No. 42,498. (No model.)

To all whom it may concern:

Be it known that I, ERNST JOSEPH SCHMIDT, a citizen of Germany, residing at Hamburg, Germany, have invented certain new and useful Improvements in Boiler-Furnaces, of which the following is a specification.

This invention relates to a boiler-furnace in which an intimate admixture of the fire-gases with the air is effected, so that an improved combustion is obtained.

In the accompanying drawings, Figure 1 is a vertical longitudinal section of a boiler-furnace provided with my improvement. Fig. 2 is a horizontal section on line A B, Fig. 1; Fig. 3, a cross-section on line C D, Fig. 1; and Fig. 4, a cross-section on line E F, Fig. 1.

The letter *a* represents the grate of a boiler-furnace, and *c* is the hollow fire-bridge provided with a grated sleeve *b*, which serves for the secondary supply of air.

d is the hurtle-arch set back at a proper distance from the fire-bridge.

The top of the fire-bridge *c* dips from one side toward the other side of the combustion-chamber, the drawing Fig. 3 showing it inclined from left to right. The upper edge *d'* of arch *d* also dips from left to right, Fig. 4, so that in this way an increased opening of

the fire-bridge is longitudinally in line with a reduced opening of the arch. The arch *d* ³⁰ is furthermore set obliquely to the longitudinal axis of the combustion-chamber, Fig. 2.

By the construction described greater quantities of fire-gases will pass over the right half of the fire-bridge than over the left half, while ³⁵ the right side of the hurtle-arch will offer a reduced opening for the passage of such gases. Thus the fire-gases must flow laterally as well as rearward, so that they assume a tortuous or diagonal course. This peculiar flow of ⁴⁰ gases will cause their intimate admixture with the air supplied by the hollow fire-bridge, so that an improved combustion is effected.

What I claim is—

A boiler-furnace provided with a fire-bridge ⁴⁵ that dips from side to side, and with an obliquely-set hurtle-arch that also dips from side to side, to form a tortuous passage for the fire-gases, substantially as specified.

Signed at Hamburg, Germany, this 20th day ⁵⁰ of December, A. D. 1900.

ERNST JOSEPH SCHMIDT.
